UNITED STATES PATENT OFFICE

OTTO M. SUMMERS, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed July 30, 1927. Serial No. 209,546.

This invention relates to mechanical household refrigerators and particularly to devices for freezing blocks or cubes of ice for table use.

It is among the objects of the present invention to provide a container or tray for ice blocks which is convenient to handle and easy to fill, which freezes ice quickly, and which facilitates the removal of the frozen blocks.

It is also an object of the invention to provide an improved container which is economical to manufacture.

Further objects and advantages of the present invention will be apparent from the following description, reference being had to the accompanying drawings, wherein a preferred form of embodiment of the present invention is clearly shown.

In the drawings:

Fig. 1 is a perspective view of an inverted ice tray constructed in accordance with my invention;

Fig. 2 is a perspective view of such a tray right side up; and

Fig. 3 is a longitudinal section thru an ice tray in the freezing chamber of a mechanical household refrigerator.

In almost every mechanical household refrigerator in use at the present time, some provision is made for freezing cubes or blocks of ice for table use. As shown in Fig. 3, in connection with the present invention, this is usually in the form of a shallow pan or tray 10, which is placed in a support 11 in a freezing chamber 12 provided for that purpose in connection with the evaporator or cooling unit 13 of the refrigerating system. Such trays are usually subdivided into compartments or else are provided with partitions, such as removable grids, for the purpose of defining the blocks of ice.

The previously known trays have not been entirely satisfactory because it is difficult to remove the ice blocks after they are frozen. It has usually been necessary to melt loose the entire contents of the tray, separate the desired number of blocks from the mass, and then replace the remainder. This is unsatisfactory and annoying. Attempts to solve this

problem have been made by freezing the blocks in cups arranged in racks so as to be individually removable. But this proposal has not met with success because such arrangements froze ice slowly, because they seriously reduced the ice capacity of the tray, because it is tedious to fill a lot of little cups, and because it is very difficult to fill them at all without spilling water, which then runs over the sides and freezes the rack or cups to the support when the tray is placed in the freezing chamber.

Furthermore, such structures as have been made are quite expensive to manufacture and are undesirable for this reason.

In accordance with my invention I form an ice tray of a plurality of individual cups which are placed compactly together and fastened in a frame in such a manner that they form a single imperforate container divided into compartments.

Each cup 16 is preferably drawn or stamped from a single thin sheet of metal, such as copper, and as shown in the drawings, each cup is roughly cubical, being more accurately described as the frustum of a four-sided pyramid having rounded corners. The open ends 17 of the cups are rectangular, or as nearly so as can be conveniently formed in manufacturing. Any desired number of cups are assembled with their upper edges in contact, and are so secured together to form a unitary, partitioned container. Preferably the cups are placed within a frame, or band 18, flush with the top edges 17, and while so assembled, the band and cups are dipped in molten solder, or other suitable bonding material, which effectively solders together the edges 17 of the cups and solders the group of cups into the frame.

The frame 18 which holds the cups together may be of any form which is suitable to manufacturing conditions and the evaporator with which the apparatus is to be employed. As shown for the sake of illustration in the drawing this frame comprises a U-shaped member 18^a whose ends 18^b are turned in to facilitate attachment to the plate 19 which serves both as a handle and as a closure for the freezing chamber as is well known in the

art. A cross member 18^a is placed in the U-shaped member an appreciable distance behind the handle and within this rectangle formed between the U-shaped member 18^a and the cross member the desired number of cups are placed. The dimensions of the cups and the frame are such that the frame binds the cups quite firmly together and holds them in this assembled relation while they 10 are being dipped in molten solder.

As is seen in Fig. 2, the corners of the upper edges of the cups are not perfectly square, but are rounded slightly. This is due to the manufacturing process, it being difficult and 15 expensive to make cups with perfectly sharp corners. Each of the spaces between the corners may be filled with a bead of solder 19, after the dipping operation, in order to make an imperforate container, in case the dipping 20 operation does not fill the openings. Each cup may taper for its full depth so as to contact with adjacent cups at the upper edges only, as shown in the left hand portion of Fig. 3, or each cup may have sides which are 25 parallel for a substantial distance down from the top, so that the cups will be in contact thruout a substantial portion of their height, as shown in the right hand portion of the same figure. The former arrangement facilitates 30 removal of ice blocks by allowing hot water to come in contact with a greater portion of the cups, while the latter arrangement considerably facilitates assemblage of the cups in the frame during manufacturing. 35 Either arrangement reduces to a negligible quantity, that is, to a thin edge, the distance between the tops of adjacent cups. Consequently, in filling the cups, all that is necessary is to pour water into the group of cups. 40 Due to the thin edges between cups, all of such water must fall into the cups. None can run off between cups, and all water overflowing from any cup, except the outside ones, must necessarily flow into adjacent cups. No 45 water can flow down between cups, and this minimizes the likelihood of getting water on the bottom or sides of the tray, which would cause it to freeze to its support 11 in the freezing chamber.

50 Due to their tapering form, the cups are separated from each other thruout a substantial portion of their height, and the bottom of the tray is thus subdivided by a number of mutually transverse grooves, which, it will be noted, extend continuously across the full length and breadth of the tray, and as has been noted, may extend substantially the full thickness of the container, that is, from bottom to top of the ice tray. In other words, 55 this form of construction provides a tray which is subdivided into a plurality of compartments by mutually transverse sets of hollow walls, and the walls have sharp upper edges for deflecting into the compartments 60 all water which may be poured into the tray.

When it is desired to fill the tray, the latter is simply held under a faucet, and water is run into any of the cups. The over flow from the cups directly under the faucet fills the neighboring cups and thus fills the 70 tray quickly. After this, the tray may be tipped slightly for an instant to equalize the level of the water in all the cups, and to bring this level to the desired point. Excess water flows off the side of the tray, can not 75 get between cups, and is not likely to get on the bottom of the tray in any appreciable quantity. The tray may then be placed in the freezing chamber without likelihood of being frozen to its support. 80

When it is desired to remove one or more ice blocks from the tray, the latter is inverted, as shown in Fig. 1 and held under a warm water faucet. Due to the particular conformation of the bottom of the tray, the 85 warm water may flow over any given block or group of blocks so as to dislodge the blocks or group of blocks selected without disturbing the remaining blocks in the pan. For example, suppose it is desired to remove the block in cup 20 in Fig. 1. The cup 20 is held directly under the faucet, and warm water flows over and entirely around this cup. All four walls of the cup being warmed, the block is immediately dislodged. The warm 90 water flows off thru the grooves between the other blocks, for instance thru grooves 21, 22 and 23. This naturally can melt loose one side of each of blocks 30 and 31, sides 32 and 33 of block 34, sides 35 and 36 of block 95 37 and sides 38 and 39 of block 40. But it will be noticed that the pan can be held so that all the water runs off thru grooves 21, 22 and 23. Therefore the sides not mentioned of blocks 30, 31, 34, 37 and 40 will not be 100 melted away from the cups and these blocks 105 will consequently remain frozen in the tray. Likewise suppose it is desired to remove an entire group of blocks, such as 41, 42 and 43. In this case the row 41, 42 and 43 is passed 110 back and forth under the warm water faucet so that the water flows entirely around each of the blocks mentioned. The water flows off thru the grooves between the other blocks but does not completely surround any other 115 block. Thus all other blocks are left with one or more sides frozen to the cups and are consequently retained in position. Other groups, differently arranged, may be removed in a similar manner. This arrangement is 120 of great advantage since it permits the freezing of blocks of different flavors and colors at the same time in the same pan and permits the removal of any one or any group of such flavors or colors without disturbing the remaining blocks. 125

Another advantage resulting from this construction is the rapidity with which the blocks may be frozen. Each cup rests directly on the support 11 in the freezing chamber 130

and is thus in good thermal contact with such support. Each block of ice is completely surrounded by metal conducting elements which are integral with each other and with the bottom which contacts with the support in the freezing chamber. This provides an excellent multiple path for conducting the heat out of the water.

It has also been found that the form of ice tray shown is considerably cheaper to manufacture than the present conventional type of tray, that is, one having a removable grid which is placed within the pan. The grids have proved to be particularly expensive to manufacture, and altho it may not be self evident, it has been found from actual trial that it is much more economical to stamp the individual cups and assemble them in a frame than it is to manufacture a pan and a grid.

While the form of embodiment of the present invention as herein disclosed, constitutes a preferred form, it is to be understood that other forms might be adopted, all coming within the scope of the claims which follow.

What is claimed is as follows:

1. A container for making a plurality of ice blocks in household refrigerators having its under side divided into sections by mutually transverse sets of continuous grooves of substantially the same depth, the grooves being adapted to receive warm water for disengaging the ice blocks and extending through the sides of the container to permit water to drain from the grooves.

2. A container for making a plurality of ice blocks in mechanical household refrigerators having mutually transverse partitions dividing the interior of the container into compartments, the under side of the container being divided into sections corresponding to the compartments by grooves of substantially the same depth extending continuously across the under side and through the sides of the container and adapted to receive warm water for disengaging the blocks.

3. A container for making a plurality of ice blocks in mechanical household refrigerators having mutually transverse sets of double-walled partitions extending from the bottom to the top of the container and dividing the interior of the container into compartments.

4. A container for making a plurality of ice blocks in mechanical household refrigerators having mutually transverse sets of double-walled partitions dividing the interior of the container into compartments, the under side of the container having grooves of substantially the same depth extending continuously across the container and through the sides of the container between the walls of the partitions.

5. A container for making a plurality of ice blocks in mechanical household refriger-

ators comprising a plurality of cups each adapted to make a block of convenient size for table use, said cups being joined at their open ends to form a partitioned container, and being separated at their closed ends to permit passage of warm water around individual cups, whereby one or more individual blocks of ice may be disengaged from the container without loosening the remaining blocks.

6. A container for making a plurality of ice blocks in mechanical household refrigerators comprising a plurality of cups each adapted to make a block of convenient size for table use, said cups being joined at their open ends to form a partitioned container, and being separated at their closed ends to permit passage of warm water around individual cups, the joints between the cups forming edges adapted to deflect into the cups all water poured into the container.

7. A container for making a plurality of ice blocks in mechanical household refrigerators comprising a plurality of cups each adapted to make a block of convenient size for table use, said cups being joined at their open ends to form a partitioned container, and being separated at their closed ends to permit passage of warm water around individual cups, the spaces between the cups being closed and forming edges adapted to deflect into the cups all water poured into the container.

8. A container for making a plurality of ice blocks in mechanical household refrigerators comprising in combination a U-shaped frame, a cross member between the arms of the frame, said arms extending beyond the cross member, a plurality of cups secured to each other and secured within the space between said cross member and the frame, and a handle secured to the ends of the arms.

9. A container for making a plurality of ice blocks in household refrigerators having its under side divided into sections by mutually transverse sets of continuous grooves extending substantially the full height of the container, the grooves being adapted to receive warm water for disengaging the ice blocks.

In testimony whereof I hereto affix my signature.
